UNITED STATES PATENT OFFICE

115,860

DESIGN FOR A BASEBALL GAME DEVICE

Harry K. Surbeck, Cleveland, Ohio

Application October 6, 1938, Serial No. 80,290

Term of patent 3½ years

To all whom it may concern:

Be it known that I, Harry K. Surbeck, a citizen of the United States, residing at Cleveland, in the county of Cuyahoga and State of Ohio, have invented a new, original, and ornamental Design for a Baseball Game Device, of which the following is a specification, reference being had to the accompanying drawing, forming part thereof.

Fig. 1 is a front perspective view of a baseball game device, showing my new design.

Fig. 2 is a fragmentary perspective view of the rear portion of the device on an enlarged scale.

I claim:

The ornamental design for a baseball game device, as shown.

HARRY K. SURBECK.
